UNITED STATES PATENT OFFICE.

ALEXANDER B. RONEY, OF CHICAGO, ILLINOIS.

MOTOR.

SPECIFICATION forming part of Letters Patent No. 717,624, dated January 6, 1903.

Application filed October 10, 1901. Serial No. 78,182. (No model.)

To all whom it may concern:

Be it known that I, ALEXANDER B. RONEY, a citizen of the United States, residing at Chicago, county of Cook, and State of Illinois, 5 have invented new and useful Improvements in Rotary Motors, of which the following is a specification.

The object of my invention is to provide a motor that is self-starting and self-contained 10 while propelling a loaded vehicle. It has other mechanical advantages relating to its application to traction - vehicles explained elsewhere.

Figure No. 1 is an outline view of a vehicle 15 to which my invention is applied. Fig. No. 2 is a vertical section of Fig. 1 on the line 2 2 as indicated by dotted line 4 4 in Fig. 4. Fig. No. 3 is a cross-section of Fig. 1 on the line 2 2. The figure shows the thrust-plate 20 J^2 , the spoke-wheel A^{24} , and the torch A' removed for purposes of illustration. Fig. No. 4 is a cross-section of Fig. 1 on the line 3 3. Fig. No. 5 is a cross-section of the coupler A^9 and axle R . Fig. No. 6 is a longitudinal section of Fig. 7. Fig. No. 7 is an outline view of the expander.

My invention consists of elementary parts in combination, as follows: first, the axle R ; second, the wheel H' , loose on the axle R , 30 with its periphery spaced off in notches A^{23} ; third, an endless chain of piston-expanders, consisting of piston and cylinder parts $M^2 M^3$, movable in guides $S' S^2$ at striking distance to the notches A^{23} of the wheel H' ; fourth, 35 the expanders filled with a volatile fluid and sealed tight by a fusible packing; fifth, the application of heat to the body of one or more expanders in the chain to expand the fluid in them against their pistons the instant the end 40 of piston part M^3 of any expander in the chain is in the position past the dead-center of wheel H' , so that it will enter a notch A^{23} and push the wheel around; sixth, a feed mechanism consisting of shaft C' , spoke-wheel A^{21} , 45 and thrust-plate J' , actuated by the wheel H' to move the guided expanders, on the one hand, to be heated for action against the wheel H' , on the other, through a cooling-bath to condense the heated fluid in them 50 back to its original state, thence again to the heat, thence to be cooled, and so on continuously while the heat is applied to them.

The utility of my invention is best explained by showing it, as illustrated, compounded and assembled, in combination with 55 the running-gear of a vehicle as a driver. It is not necessary to compound the motor for both the forward and back-up propulsion, as shown, other than to avoid the use of differential gearing for the back-up propulsion and 60 have a motor in reserve in case the one breaks down. The conditions of automobile propulsion require in order that the vehicle be self-contained that all of its useful characteristics can be asserted and controlled by one 65 simple steering-lever.

The manner in which the motor is harnessed to the vehicle as a driver, the manner in which it propels it, and the manner in which its operation is controlled by a single 70 lever are explained as follows:

A pair of motors, each one having the elementary parts in combination as itemized, is mounted to a vehicle, of which Fig. 1 is an outline view. Fig. 4 shows the notched wheels 75 $H' H^2$ of each motor loose on the axle R , with the splined coupler A^9 loose on the axle between them. The peripheries of motor-wheels $H' H^2$ are divided up in notches A^{23} , and the space between the notches coincides with the 80 spacing of the expanders that are supported by and adapted to travel tandem between guides $S' S^2 S^3 S^4$, so that their piston parts M^3 register in relative order in striking distance to the notches A^{23} of the wheels $H' H^2$. 85 The guides $S' S^2 S^3 S^4$ are filled with expanders throughout their continuous path, inclined on the one side down into the water-trough and on the other side inclined up out of the trough into a horizontal plane over the motor-wheels 90 $H' H^2$, but under the thrust-plates $J' J^2$, thence around to the incline at the other side. The expanders, held in the guides under the thrust-plates $J' J^2$, but over the wheels $H' H^2$, 95 are in mesh with the spokes of the wheels $A^{21} A^{24}$. The spoke-wheel A^{24} (not shown) is similar to the spoke-wheel A^{21} and is mounted on the shaft C^2 just below the thrust-plate J^2 . Both the spoke-wheels and the thrust-plates are fixed to the vertical shafts $C' C^2$, that have 100 gears meshed in the hub-gears $F' F^2$ of wheels $H' H^2$. The shaft A^{20} is located in bearings at suitable distance from the wheels $H' H^2$ and axle R . It has an arm A^8 in connection

with the coupler A⁹ on the axle R. It supports a gasolene-torch, which is fixed to it. The valve-stem of the torch is in gear with the rack extension of the splined collar A⁴, which is loose on the shaft A²⁰ and which has an annular groove in which plays the forked end of pivoted lever A⁵. The spring N under the collar A⁴ rests on the gear-wheel A⁷. Gear-wheel A⁷ is fixed to the shaft A²⁰. The gear-wheel A⁷ is in mesh with the rack A⁶. The rack A⁶ extends through the hangers P' P' and connects with the link A¹⁹. The link A¹⁹ connects with the steering-lever A¹⁵, and the steering-lever is hinged to shaft A¹⁸ of the forward trucks. The steering-lever A¹⁵ has a knurled sleeve A¹⁴ loose on one of its handle-bars. Then one end of cord A²² is attached to the sleeve, and the other end of the cord is tied to the pivoted lever A⁵. Any one of the expanders is a piston device. (See Figs. 6 and 7.) The cylinder part M² is made of seamless tubing, with one end plugged to seat the valve M⁵. It is ground out true, perfectly straight, and absolutely smooth. The piston part M³ has annular grooves filled with a fusible packing that melts at a temperature of boiling water. The piston is machined true, straight, and smooth, so as to telescope the cylinder with a snug fit. Within the expanders are coiled springs M', that hold the parts M³ M² together. Then the expanders are filled with a volatile fluid and sealed tight by drawing the threaded valve to its seat by the nut N⁶.

35 The gasolene-torch, mounted on shaft A²⁰, is first fired up before operating the motors. Then the operation is confined to but one motor at a time. Now moving the steering-lever A¹⁵ moves the link A¹⁹. The link moves 40 the rack A⁶ to rotate the shaft A²⁰, which turns the flame of the torch onto the expanders in position over the notched wheel H². In addition to this the same rotation of shaft A²⁰ moves the coupler A⁹ into clutch with the 45 wheel H², locking it to the axle R. Then if the knurled sleeve A¹⁴ on the handle-bar of the steering-lever is turned to wind in the cord A²² to throw the lever A⁵ and move the rack guided by the splined collar A⁴ to open the 50 valve A³ of the torch this regulates the intensity of heat applied to the expanders. Now the expanders that are subjected to the heat of the torch are just by the dead-center of the notched wheel H². Then the metal 55 packing within the expanders melts and packs the piston-joints in the cylinders effectually against leakage. Then the volatile fluid within them expands and forces the cylinder

parts M² against the thrust-plate J², while the piston parts M³ are forced against the notches 60 faces A²³, thus rotating the combined wheel and axle. The wheel H² in its turning turns the shaft C², which with its spoke-wheel A²⁴ moves the live expanders away from the wheel H² along the guides S³ S⁴ to the water-trough; but before the live expanders could reach the water-trough the pressure in them would force their pistons out were it not for the tension of the powerful coiled springs that hold them in while in transit along the 70 guides to be cooled off for the condensation of their volatile fluid. The condensing fluid creates a vacuum that draws the pistons back into the cylinders, assisted by the springs. Now the vehicle is being propelled in the 75 backward direction, and the speed of its propulsion is regulated by the use of the knurled sleeve A¹⁴ to wind or unwind the cord A²² to open or to shut the valve of the torch. Then to allow the momentum of the vehicle a free 80 wheel the steering-lever is moved forward just enough to move the coupler A⁹ to uncouple the motor-wheel H² from the axle R and at the same time swing the flame of the 85 torch away from the expanders. Then the motor-wheels H' H' being loose on the axle and spaced far enough apart allow the axle R to revolve the coupler A⁹ without touching the wheels. Now for the forward propulsion of the vehicle the steering-lever is moved still 90 forward to move the coupler A⁹ to clutch the wheel H' of the other motor and lock it to the axle R, and the torch responding to the same movement of the steering-lever swings with its flame against the expanders of the other 95 motor to actuate them in the manner described.

What I claim as my invention, and desire to secure by Letters Patent, is—

In a rotary motor, the combination of an 100 axle, and a wheel on said axle having its periphery spaced off in notches, with a chain of piston-expanders, containing a volatile fluid, heating appliances, cooling means and a feed 105 mechanism for moving the expanders into position over the notched wheel on the axle, where the expanders are subjected to the heating appliance, whereby the pistons of the expanders are forced outward into the engagement with the notched wheel, said feed mechanism then moving the expanders to the cooling means.

ALEXANDER B. RONEY.
